UNITED STATES PATENT OFFICE

2,404,398

TREATMENT OF WINERY SLOPS

Ellis C. Pattee, Cincinnati, Ohio, assignor to National Distillers Products Corporation, a corporation of Virginia

Application March 29, 1943, Serial No. 480,919

6 Claims. (Cl. 99—5)

1

This invention relates to the production of usable by-products from winery still slops and will be fully understood from the following description read in conjunction with the drawing which is a diagrammatic side elevation of apparatus in which the invention may be carried out.

Referring to the drawing, the slops in tank 1 may be bottoms from the distillation of the liquor obtained by washing and/or pressing pomace or bottoms from the distillation of lees. The slop is withdrawn from tank 1 into mixer 2 in which it is heated, while undergoing mixing, by steam supplied to coil 3. The mixing and heating are necessary to compensate for any cooling and consequent precipitation of potassium acid tartrate that may occur between the time the still slop is withdrawn from the still and the time it is supplied to the potassium acid tartrate recovery system. From the mixer the heated slops is fed continuously to the bowl of the imperforate overflow centrifuge 5. The suspended organic matter present in the slops is separated as a cake in bowl 4 from which it is intermittently dumped and by means of conveyor 5' combined with pressed pomace moving continuously forward on conveyor diagrammatically indicated by 6. The overflow from bowl 4 is still slops clarified and freed of suspended organic material; this is picked up in collector ring 7 and diverted through pipe 8 into tank 9.

In some instances the still slops contains practically no suspended solids and the clarification step may be omitted.

From tank 9 the clarified still slops is supplied continuously through pipe 11 into the first unit 12 of a multiple effect evaporator in which it is heated indirectly by steam introduced through pipe 13, condensate from the steam passing off through pipe 14. The steam produced by heating the still slops passes through pipe 15 into evaporator unit 16 while the partly-concentrated slops moves forward through pipe 17 into the body of evaporator unit 16 in which it is heated indirectly by the steam introduced through pipe 15, condensate therefrom passing off through pipe 18. The steam produced by evaporation in unit 16 passes off through pipe 19 into barometric condenser 21 in which it is condensed, by water introduced through pipe 22, to maintain the necessary stages of vacuum at which evaporation and concentration of the slops will take place in units 12 and 16.

The concentration in these units is carried out to a point at which the potassium acid tartrate is

2

present in excess of the amount which is soluble in the slops at a lower temperature, and preferably to a point at which the major part of the potassium acid tartrate will be insoluble at the lower temperature. With a salt type evaporator this concentration may be carried forward to form a viscous solution containing crystals of potassium acid tartrate.

The extent of concentration required will, of course, depend upon the amount of potassium acid tartrate initially present and this in turn will depend upon the source from which the still slops was derived, the amount of wash water used, the amount of lees in the material distilled and various other factors.

The concentrated clarified still slops is then passed through pipe 23 into crystallizing tank 24 in which it is cooled to a temperature at which the bulk of the potassium acid tartrate passes out of solution, under conditions adapted to hold the crystals of potassium acid tartrate so formed in suspension and prevent their accumulation in the crystallizing tank. From tank 24 the concentrated slops containing the suspended crystals of potassium acid tartrate passes continuously through pipe 25 into bowl 26 of centrifuge 27. The bowl is of the imperforate overflow type or the perforated type; the crystals accumulate as a cake therein and are intermittently dumped or continuously abstracted and passed into dryer 27 in which they are heated by steam passing through coil 29 to form a crude substantially dry potassium acid tartrate. The overflow from bowl 26 consisting of the still slops that has been clarified, concentrated and substantially freed of potassium acid tartrate is passed continuously through pipe 31 into the pressed pomace moving forward on conveyor 6. It is thoroughly mingled with the pomace in mixer 32 and moves thence on conveyor 33 into steam dryer 34 within which it is heated to substantial dryness by means of steam.

The dried material consisting of pomace and the soluble materials (other than potassium acid tartrate) originally present in the winery still slops moves through air conveyor 35 into hopper 36 from which it flows continuously to the grinder 37 in which any lumps are disintegrated and thence into storage tank 38 from which it may be sacked or transferred to cars for bulk shipment.

The amount of concentrated clarified still slops, dry basis, should range from 2.0 to 20.0% by weight of the pomace, dry basis.

The combined dry material is used as a cattle and poultry food and is both more desirable and

valuable for this purpose than is the dried pomace alone.

The foregoing description is for purposes of illustration and not of limitation and it is therefore my intention that the invention be limited only by the following claims or their equivalents wherein I have endeavored to claim broadly all inherent novelty.

I claim:

1. Process of obtaining usable by-products from winery residues, including winery still slops containing potassium acid tartrate which comprises evaporating said still slops, separating crystals of potassium acid tartrate therefrom, combining the residual evaporated still slops with pomace and drying the combined materials.

2. Process of obtaining usable by-products from winery residues, including winery still slops containing potassium acid tartrate which comprises evaporating said still slops, cooling said still slops, separating crystals of potassium acid tartrate therefrom, combining the residual evaporated still slops with pomace and drying the combined materials.

3. Process of obtaining usable by-products from winery residues, including winery still slops containing suspended organic matter and potassium acid tartrate which comprises separating said winery still slops while hot into a mud cake and a clarified effluent, evaporating said effluent, cooling said evaporated effluent, separating crystals of potassium acid tartrate from said evaporated cooled effluent, combining the residual effluent with pomace and drying the combined materials.

4. Process of obtaining usable by-products from winery residues, including winery still slops con-

5 taining suspended organic matter and potassium acid tartrate which comprises separating said winery still slops while hot into a mud cake and a clarified effluent, combining said mud cake with pomace, evaporating said effluent, cooling the said evaporated effluent, separating crystals of potassium acid tartrate from the said evaporated cooled effluent, combining the residual effluent with the pomace and drying the combined materials.

10 5. Process of obtaining usable by-products from winery residues, including winery still slops containing suspended organic matter and potassium acid tartrate which comprises introducing said winery still slops while hot into a rotating mass of the same defining a tubular inner wall, thereby separating a mud cake and a clarified effluent, evaporating said effluent, cooling said evaporated effluent, separating crystals of potassium acid tartrate from said cooled evaporated effluent, combining the residual effluent with pomace and drying the combined matter.

15 6. Process of obtaining usable by-products from winery residues, including winery still slops containing suspended organic matter and potassium acid tartrate which comprises introducing said winery still slops while hot into a rotating mass of the same defining a tubular inner wall, thereby separating a mud cake and a clarified effluent, 20 combining said mud cake with pomace, evaporating said effluent, cooling the said evaporated effluent, separating crystals of potassium acid tartrate from the said evaporated cooled effluent, combining the residual effluent with the said pomace and drying the combined materials.
